US00D824908S

(12) **United States Design Patent** (10) Patent No.: **US D824,908 S**
(45) Date of Patent: **** Aug. 7, 2018**

(54) **HAND-HELD INVENTORY DATA
COLLECTION DEVICE**

(71) Applicant: **RGIS, LLC**, Auburn Hills, MI (US)

(72) Inventors: **Gregory Paul Schooneveldt**,
Melbourne (AU); **David Allen Gehrke**,

Pierce, P.L.C.

(57) **CLAIM**

The ornamental design for a hand-held inventory data collection device, as shown and described.

DESCRIPTION

FIG. 1 is a front, right side, bottom perspective view of a hand-held inventory data collection device;

FIG. 2 is a front view thereof;

FIG. 3 is a top view thereof;

FIG. 4 is a bottom view thereof;

FIG. 5 is a right side view thereof;

FIG. 6 is a left side view thereof; and,

FIG. 7 is a back view thereof.

The broken lines in FIGS. 1-7 illustrate portions of the hand-held inventory data collection device that form no part of the claimed design.

1 Claim, 6 Drawing Sheets
